UNITED STATES PATENT OFFICE.

FREDERICK GRINHAM, OF ST. LOUIS, MISSOURI, ASSIGNOR OF ONE-THIRD TO OLIVER J. SAVIN, ONE-SIXTH TO JOHN C. STILES, AND ONE-SIXTH TO HUGH K. WAGNER, ALL OF ST. LOUIS, MISSOURI.

APPARATUS FOR IMPROVING AND INCREASING THE USEFUL RESULTS OBTAINABLE FROM GASOLINE OR OTHER FUEL IN INTERNAL-COMBUSTION ENGINES AND THE LIKE.

Application filed March 7, 1921. Serial No. 450,284.

To all whom it may concern:

Be it known that I, FREDERICK GRINHAM, a citizen of the United States, residing at the city of St. Louis, in the State of Missouri, have invented certain new and useful improvements in apparatus for improving and increasing the useful results obtainable from gasoline or other fuel in internal-combustion engines and the like, of 10 which the following is a specification.

This invention consists of apparatus for deriving larger results from the fuel used in internal-combustion engines and the like. The said object is attained in two ways: 15 (1) By extracting part of the products of combustion from the exhaust manifold by means of a by-pass, cut-off, pipe, valve, or other suitable means and feeding the same into the intake manifold or into the engine 20 at any other suitable point; (2) part or the whole of the residue of the said products of combustion is suitably caught, and may be bottled or otherwise preserved in suitable receptacles or reservoirs, whereupon it 25 is later used for various useful purposes. The capture or taking of the products of combustion out of the exhaust must be accomplished in such a way as not to choke the engine. If desired, all of the products 30 of combustion may be taken without extracting part for refeeding to the same engine.

By the first means above stated, the valuable original fuel that is held in a waste 35 condition in the products of combustion is reused until ultimately consumed. It is well known that such wasted fuel amounts prior to this invention to about sixty per cent (60%) of the fuel used. All this can be 40 saved. Moreover, it has been found by actual trial with a motor-vehicle that the mileage obtained with a given quantity of gasoline is quadrupled when this invention is used as compared to when it is not, other 45 conditions being the same. Furthermore, it has been observed in actual practice when this invention is used that grease upon a 50 spark-plug is immediately removed when this invention is put into use, contrary to the condition when this invention is not in use, and that the said cleansed condition continues while the use of this invention is 55 maintained. This is due in part to the heat

contained in the products of combustion when extracted from the exhaust manifold 55 or other suitable point in the engine and fed into the intake manifold or other suitable part of the engine. It is due, also, to the chemical composition of the said products of combustion. 60

By the second means above stated, a valuable chemical or compound is saved from wasting into the atmosphere and being there lost, and the said chemical or compound is thus saved, and, on trial, has been found 65 adapted for various useful purposes, not all of which are yet known, but among which may be mentioned the following: (1) It can be and has been used for light, like ordinary illuminating gas, flaming from an 70 ordinary gas jet or burner, and in such use may be used, as an example, to light a shop in which the engine is located that produced it. (2) When held in a proper receptacle, a suitable reagent may be used, thereby causing 75 such a separation into constituent elements as allows the drawing off of that part which, when introduced into the intake-manifold of an internal-combustion engine, magnifies its results. The said valuable part may be separately bottled or conducted to reservoirs and dispensed in such 80 containers or from such reservoirs in receptacles or by pipes or in any suitable manner. The other separated elements may or 85 may not be preserved and used. The chemical or compound as a whole, however, namely the products of combustion of an internal-combustion engine, has never before been known to have any value, and this value 90 having been discovered by the present inventor, it is its utilization for any and all purposes that is herein contemplated, in contradistinction to the waste thereof which is now universal. 95

In the accompanying drawings forming a part of this specification, in which like numbers of reference denote like parts wherever they occur,

Figure 1 is an elevation showing a pipe 100 connection from the exhaust to the intake of an internal-combustion engine;

Figure 2 is an elevational view, partly in section, showing a pipe connection between the exhaust manifold of an internal-combustion engine and a reservoir tank for stor- 105

ing the products of combustion and a gas-pipe and burner or gas-jet; and

Figures 3 and 4 illustrate modifications relative to the valve connections.

5 Referring to Figure 1, pipe 1 leads from exhaust manifold 2 to intake manifold 3, and therethrough are conducted the above-mentioned products of combustion, the quantity thus passing being controlled by 10 the valve 4. The internal-combustion engine 5, with its carbureter 6, intake 3, exhaust 2, pipe 1, and valve 4 are shown in the drawings in conventional forms and, in fact, almost diagrammatically, as this invention 15 resides in the broad discovery above stated and any mechanism for putting it into practical use and not in mechanical details, although the drawings illustrate an arrangement of mechanism that in practice has 20 been satisfactorily and successfully operated.

Referring to Figure 2, pipe 7 resembles pipe 1 in function and leads from the exhaust 8 to a reservoir 9, where the products 25 of combustion are stored like gas (for instance, ordinary illuminating gas), and emitted through pipe 10 and burner 11, which may be an ordinary gas-jet, such emission being controlled by cock 12. Any 30 suitable valve, such, for instance, as an ordinary ball check-valve 13 controls the passage of the gas through pipe 7. The pulsations of the engine force the gas past valve 13, and the gas is then stored in tank 35 9. Any suitable valve may be used for valve 4 in pipe 1, the one shown being of the needle type.

While hereinabove reference has been made rather specifically to the exhaust manifold and to the intake manifold, yet it is to be understood that by this term is to be included any part of the exhaust or even of the engine whence the products of combustion can be derived. These remarks apply, also, to Figures 3 and 4, in which the same general application of the terms intake 14 and exhaust 15 is to be understood.

As other illustrative mechanical means for carrying out this invention, Figures 3 50 and 4 show examples of suitable valves 16 and 17, but other forms of valves besides these and those shown in Figures 1 and 2 may be used.

In Figure 3, pipe 18 leads from exhaust 55 15 to valve 16, while pipe 19 leads from valve 16 to intake 14. A sliding cup 20 within the casing 21 of valve 16 is provided with an opening or plurality of openings 22, with which registers pipe 18 at certain 60 intervals, whereby cup 20 is caused to slide within casing 21, which causes the flow of the gas (products of combustion) from pipe 18 into cup 20 to cease, but such gas

within cup 20 flows out through port 23, passage 24, and pipe 19 into intake 14, the 65 quantity of such discharge being controlled by needle-valve 25 or other suitable means.

In Figure 4, pipe 26 leads from exhaust 15 to intake 14, passage of gas (products of combustion) therethrough being controlled 70 by needle-valve 27. The pulsations of the engine actuate diaphragm 28 first in one direction and then the opposite, which results in reciprocation of the stem 29 of valve 27, with the result that pipe 26 is alternately opened and closed. Diaphragm 28 is 75 inclosed within casing 30, which communicates by means of pipe 31 to intake 14.

The products of combustion may be conducted to the intake of the engine whence 80 they came or to that of another or to an independent reservoir.

Having thus described this invention, I hereby reserve the benefit of all changes in form, arrangement, order, or use of parts, 85 as it is evident that many minor changes may be made therein without departing from the spirit of this invention or the scope of the following claims.

I claim:

1. In combination, an intake manifold, an exhaust manifold, means affording communication between the intake and exhaust manifolds, a needle valve controlling the passage of fluid through said means, and 95 means controlled by and communicating with the intake manifold for closing communication between said manifolds upon increase of pressure in the intake manifold.

2. In combination, an intake manifold, an exhaust manifold, a pipe extending from the intake manifold, a needle valve case screwed on the end of said pipe and provided with a laterally opening passage communicating with the pipe, a needle valve 105 screwed in said casing and controlling the flow of fluid through said passage, a chamber secured to said needle valve casing and having communication with the pipe through the lateral opening, a valve in said 110 chamber comprising a hollow cylinder closed at its bottom and open at its top, said cylinder being provided intermediate its ends with an external groove and ports opening from the groove into the interior 115 of the cylinder, said cylinder being further slidable vertical in its casing, and a second pipe connecting the last mentioned casing with the exhaust manifold, said cylinder being movable in its casing to bring the groove into and out of register with the opening in the last mentioned pipe.

In testimony whereof I hereunto affix my signature.

FREDERICK GRINHAM.
